UNITED STATES PATENT OFFICE.

JOSEPH KRIZEK, OF CHICAGO, ILLINOIS.

FAN ATTACHMENT FOR ROCKING-CHAIRS.

1,281,795.

Specification of Letters Patent. Patented Oct. 15, 1918.

Application filed October 24, 1914. Serial No. 868,525.

To all whom it may concern:

Be it known that I, JOSEPH KRIZEK, a subject of the Emperor of Austria, residing at Chicago, in the county of Cook and 5 State of Illinois, have invented certain new and useful Improvements in Fan Attachments for Rocking-Chairs, of which the following is a specification.

This invention relates to fan attachments 10 for rocking-chairs and cradles in which the fan is automatically vibrated by the rocking motion of the chair or cradle.

One of the objects of my invention is the production of a simple and efficient fan attachment which can be readily attached to a 15 rocking-chair or the like and which can be manufactured at a small cost.

To these and other purposes my invention consists in the novel construction, combination and relative position of parts set 20 forth in the following specification and accompanying drawing, and more particularly brought out in the claims.

Referring to the drawings, in which like 25 reference characters indicate like or corresponding parts, Figure 1 is a front elevation of my fan attachment. Fig. 2 is a cross-section of the fan attachment taken on line 2—2 of Fig. 1, showing a rocking-30 chair equipped with said attachment. Fig. 3 is an enlarged detail showing the fan support. Fig. 4 is an enlarged illustration showing one of the means for adjusting the attachment, and Figs. 5 and 6 illustrate, re-35 spectively, front and side views of the means for locking the fan against vibrating movement.

The fan 1 is pivotally mounted on a shaft 2 which is provided with ends 2^a of smaller 40 diameter which afford shoulders 2^b which bear against the washers 3, thereby limiting the distance between the side supporting members 4 and permitting clearances 5 between the fan 1 and the member 4.

45 The vertical side members 4 are rigidly connected at their lower ends by a horizontal member 7, and pivotally mounted substantially intermediate the ends of the said members 4 and also connecting them is a 50 square member 8 having ends 8^a of a construction similar to 2^a.

Rigidly connected with angles 9 to the center of the pivoted member 8, is a slotted member 10 provided with the slot 10^a to allow for vertical adjustment with the rock- 55 ing-chair member 11 (shown in Fig. 2). A pair of bolts 12 are provided for securing the member 10.

Additional means of adjustment about the pivotal member 8 are provided by a pair of 60 bolts 13 and 14 having a pivotal connection 15. The bolt 14 is threaded nearly the entire length and two nuts 16 and 17 are furnished for regulating and locking same, and with this feature of adjustment the fan 1 65 can be better balanced by varying the angle X.

To lock the fan against vibrating movement I provide the lock member 18 having 70 a slot 18^a to coöperate with a thumb screw 19 for vertical movement. When in raised position as shown in Figs. 1, 2, 5 and 6, the U-shaped portion 18^b, projecting from the side of 18, embraces the fan 1 and prevents the swaying of same about the shaft 2. 75

From the drawings and description it is obvious that a rocking motion of the chair will impart a forward and backward vibrating movement to the fan, illustrated by Fig. 2. 80

I claim as my invention:

1. A fan attachment for rocking-chairs comprising in combination, a pivotally-suspended fan; a fan shaft; a frame comprising a pair of side members 4 having upper 85 ends connected by said fan shaft, a horizontal member 7 rigidly connecting said side members 4, a horizontal pivoted member 8, a slotted member 10 perpendicularly and rigidly connected to said horizontal mem- 90 ber 8; and means for attaching said slotted member 10 to a rocking-chair.

2. A fan attachment for rocking-chairs comprising in combination, a pivotally and freely suspended fan; a frame for said fan 95 comprising a pair of substantially vertical side members 4, means for pivotally retaining said fan between said members 4, a horizontal member 7 rigidly connecting the lower ends of the members 4, a horizontal 100 pivoted member 8 connecting said members 4 intermediate their ends, and a slotted mem-

ber 10 perpendicularly and rigidly connected with said member 8; adjustable means for balancing said fan, and means for attaching said frame to a rocking-chair.

5 In witness whereof I have hereunto subscribed my name, in the presence of two wit-

nesses, this 15th day of September, A. D. 1914.

JOSEPH KRIZEK.

Witnesses:

FRANK J. SCHRADER, Jr.,

ARTHUR P. STARR.
